DIMPLING MACHINE

Filed Sept. 30, 1943

UNITED STATES PATENT OFFICE

2,418,736

DIMPLING MACHINE

Fred J. Styres, Detroit, Mich., assignor to Chicago
Pneumatic Tool Company, New York, N. Y., a
corporation of New Jersey

Application September 30, 1943, Serial No. 504,363

3 Claims. (Cl. 153—21)

1

This invention relates to dimpling machines and particularly to a dimpling machine having a pilot for locating the aperture in the sheet relative to the dimpling dies and for automatically actuating the dies to perform the dimpling operation.

It has been the practice heretofore to provide an upwardly projecting pilot, over which the sheet containing the apertures is manipulated to have an aperture move into alignment with the pilot to permit the sheet to drop thereover. Thereafter, the operator trips a lever, by foot or hand, to produce the operation of the dies to perform the dimpling operation. It was awkward to move large sheets to align an aperture with the pilot and considerable time was lost during each movement. It also required time to manipulate the lever and the operation was tedious and fatiguing.

The present invention embodies a set of dimpling dies, provided in aligned relation. The female die is disposed on the bed of the machine, and the male die is slidably supported on an arbor which is movable relative to the fixed or female die. The male die has a pilot formation thereon, which is tapered to readily drop into an aperture and to thereafter accurately align the aperture with the axis of the die unit as the arbor is actuated to perform the dimpling operation.

A pair of contacts, carried by the male die and the arbor, engage each other after the pilot has dropped through an aperture. This closes an electric circuit to a four-way valve connected to the fluid cylinder, which moves the arbor downwardly. Valves are provided in the circuit of the cylinder for independently controlling the downward and upward movement of the arbor and a timing element is employed for holding the circuit closed after the contacts on the dies are broken. The timing element regulates the duration of the downward movement and the engagement of the dies and the sheet. Thereafter, the fluid valve is reversed and the fluid is returned from the cylinder to tank, or exhausted into the atmosphere, when air is utilized. A spring within the cylinder returns the arbor to its uppermost position as the fluid is exhausted.

During the downward movement of the arbor, a latch engages a detent on the male die and this along with the pilot is retracted by the arbor during its upward movement. This moves the pilot from the aperture, at which time the sheet is moved by the operator, after which the latch is automatically tripped to drop the die and permit the pilot to rest upon the surface of the sheet.

2

The operator has clear vision of the pilot and the next aperture to be dimpled and this may be readily and quickly aligned with the pilot to permit it to drop in the aperture, to automatically produce the operation of the device and the dimpling of the metal about the aperture.

It is to be understood that the end of the pilot may be capped with rubber, leather, or other material so as to prevent damage to the surface of the sheet when dropped thereon after each operation and the scratching of the sheet when the sheet is moved relative thereto.

A shoulder is provided on the male die, which is engaged by the wall of the arbor near the end of its downward stroke, for directly forcing the male die and the sheet against the female die, for forming the dimple in the material about the aperture.

Accordingly, the main objects of this invention are: to provide a dimpling machine which automatically operates when the pilot becomes aligned with an aperture; to provide a pilot on the top side of the sheet so that its location relative to an aperture may be readily seen by an operator; to provide a fixed female die in the bed of a machine and a male die having a body which is telescoped into the hollow end of an arbor, the wall of which engages the shoulder of the die for directly forcing the die against the sheet and female die; to provide a movable die on an arbor having a pilot which rests upon a sheet having apertures, into which the pilot drops to automatically operate the device to perform a dimpling operation; to provide a pair of contacts on the movable die and the arbor, for completing an electric circuit when the pilot drops into an aperture, for operating a valve through a timing relay which moves the arbor and die to dimple the portion of the sheet about the aperture; and, in general, to provide a device for automatically dimpling the metal about a series of apertures, which is simple in construction, positive in operation and economical of manufacture.

Other objects and features of novelty of this invention will be specifically pointed out or will become apparent when referring, for a better understanding of the invention, to the following description taken in conjunction with the accompanying drawing, wherein:

50 Figure 1 is a side view of a dimpling machine embodying features of this invention;

Fig. 2 is an enlarged broken front view of the structure illustrated in Fig. 1;

Fig. 3 is an enlarged broken sectional view of the structure illustrated in Fig. 2, taken on the

line 3—3 thereof, with the dies separated from each other; and,

Fig. 4 is a broken view of the structure illustrated in Fig. 3, with the dies moved into dimpling position.

The dimpling machine 10 comprises a base 11 and a standard 12, which supports a hydraulic cylinder 13. The top 14 of the base 11 has a female dimpling die 15 extending therethrough, substantially flush with the top of the base, as illustrated in Figs. 2, 3 and 4. The cylinder contains a piston 16 which is mounted on a piston rod 17, the upper end of which extends through the cylinder head 18, to accurately align the rod with the axis of the cylinder. The lower portion of the piston rod forms an arbor 19 having a central bore 21 in the lower end, in which the body 22 of a male die 23 is disposed for movement relative thereto. The wall 24 of the arbor 19 has a slot 25 therein through which a latch element 26 is formed on the body 22 projects.

The latch element 26 carries a contact 27 which is insulated therefrom by the insulating element 28. A spring 29 urges the body 22 outwardly of the aperture 21 in the arbor 19 with only light pressure, thereby preventing a pilot 31, on the male die 23, from damaging the surface of a sheet 32 which is to be operated upon. This sheet 32 is supported on base 11 and at a fixed level throughout the entire cycle of operation. The wall of the arbor 19 carries a contact 33 on a bracket 34, and is insulated therefrom by an insulating strip 35. A pair of conductors 36 and 37 are joined to the contacts 27 and 33 and are retained within a flexible protective sheath 38.

Spaced brackets 39 project outwardly from the side of the arbor 19 for pivotally supporting a latch element or trigger 41, having a latch head 42 which is moved toward the arbor by a spring 43. The latch head 42 engages a detent 44 on the latch element 26 when the arbor is in lowered position at the end of a dimpling operation, and upon the elevation of the arbor withdraws the die 23 and the pilot 31 from the dimple and aperture to a position above the surface of the sheet 32. After the withdrawal, the operator immediately shifts the sheet 32 to advance the next adjacent aperture toward the pilot 31. As the arbor 19 is raised a camming end 45 of the trigger 41 is engaged by a cam element 46 and the latch element 26 is released. The body 22 is then moved downwardly by the spring 29, and the end of the pilot 31 is brought again into engagement with the surface of the sheet 32. The cam element 46 is supported on a pintle 47, secured to spaced brackets 48 mounted on the cylinder. The cam element 46 is secured in camming position by a latch 49, the end of which projects into an aperture 51 in one of the brackets 48. When it is desired to interrupt the operation of the machine, the latch 49 is released, the cam element 46 swings out of position thereby becoming inoperative, and the body 22 of the male die 23 is retained in upper latched position. This permits the sheet of material 32 to be removed and a new sheet substituted therefor.

A pair of conductors 52 are connected to a source of electric current, not shown, and is joined to the conductors 36 and 37 in an outlet box 53, suitably located on the standard 12, and to conductors in a sheath 54 connected to an adjustable timing element 55, which is of the holding or time delay type for retaining its contacts closed after the contacts 27 and 33 are separated. The conductors in a sheath 56 are joined to a

solenoid 57 of a four-way valve 58, similar to a valve 31 of Merriman Patent 2,328,919. The valve 58 in one position passes fluid to the cylinder 13 and in the other position exhausts the fluid therefrom. Conduits 59 and 61 are joined to the four-way valve 58 and to the cylinder 13. The conduits contain valves 62 and 63 which control the flow of fluid being admitted or exhausted, to and from, the cylinder 13, so that the speed of movement of the male die 23 to and from the work may be adjusted to operate the same, but preferably at different speeds.

The time of the down movement and the contacting of the male die with the sheet and female die, during the dimpling operation, is controlled by the adjustable timing element 55. When the timing element operates, current is cut off from the valve, which is reversed by a spring to produce the upward movement of the male die. One or more conduits 64 are connected to the valve to conduct the fluid to the valve and away therefrom to a tank, not shown, when a liquid, such as oil, is employed, or to conduct the fluid into a cylinder, when a gas, such as air, is used, which may be exhausted directly to atmosphere upon the retraction of the arbor.

A spring 65 returns the piston to the top of the cylinder as the fluid is exhausted therefrom. The upper end of the piston rod 17 is sealed to the head of the cylinder 13 by suitable packing material 66. A bearing 67, on the lower end of the cylinder, engages the arbor and maintains it aligned with the female die. Brackets 68, which are welded or otherwise secured to the outer surface of the cylinder, support the cylinder on the end of the standard 12, when secured thereto by suitable bolts 69.

After a sheet has been completely dimpled, the latch 49 is released to prevent the cam element 46 from being operated, when the arbor is retracted. This interrupts the continuous operation of the arbor and permits the sheet, which has been dimpled, to be removed and a new sheet substituted therefor. The trigger 41 is then released by the operator to allow the pin to drop upon the surface of the sheet and the cam lever is secured in position by the latch 49. The sheet is then manipulated to permit the pilot 31 to drop into an aperture, which movement produces the engagement of the contacts 27 and 33 to complete the circuit to the timing relay 55, which operates to energize the solenoid 57 and actuate the valve 58. This admits fluid to the top of the piston 16 to force the piston downwardly. This moves the arbor 19 downwardly to move the pilot into the aperture, to accurately center the aperture relative to the dies. Thereafter, the lower end of the wall 24 of the arbor engages the male die 23 to force it downwardly to perform the dimpling operation. The set of dies and the sheet will remain in intimate contact until the operation of the timing element 55. This interrupts the circuit to the solenoid 57 and the valve 58 is spring returned to its initial position. The fluid above the piston 16 will be exhausted into the atmosphere, or a receptacle, by the action of the spring 65, which moves the arbor upwardly. Valves 62 and 63 control the speed of movement of the arbor to and from dimpling position.

During the up movement of the arbor 19, the head of the latch element 41 engages the detent 44 on the latch element 26 and the body 22 and male die 23 move upwardly with the arbor. After the pilot has been withdrawn from the aperture, the operator immediately shifts the sheet as the

further continued upward movement of the arbor causes the cam element 46 to operate the trigger 41. This releases the latch element 26 and permits the die element 23 and pilot to drop until the end of the pilot rests upon the surface of the sheet. The operator again shifts the sheet to have the next adjacent aperture moved into alignment with the pilot which drops therein and the operation above explained is automatically repeated. This is continued until all of the apertures of the sheet have had the material thereabout dimpled, after which the latch 49 is again released to prevent the trigger 41 from being actuated and the operation of the device is interrupted. The operator again removes the dimpled sheet and places the next sheet to be dimpled in position on the base.

What is claimed is:

1. In a device for dimpling the metal about apertures in a sheet of material, a stationary base for supporting the sheet at a fixed level during the entire cycle of operation, a dimpling die element rigidly supported by said base, a standard above said base, a cylinder on said standard, a piston in said cylinder, a rod on said piston, a mating die element movable on said rod and disposed in alignment with said first die element, a pilot carried by, and rigid with, said movable die element above the sheet to be worked upon, releasable retaining means for retaining said movable die element and pilot out of contact with the sheet, the base and both die elements exclusively making contact with said sheet during operation, means for releasing said retaining means to permit the end of the pilot to engage the surface of the sheet, a valve for controlling the flow of fluid to and from the cylinder, a timing element for controlling the duration of the operation of the dies when relatively moved toward each other and while remaining in contact

5

during the dimpling operation, means for returning said valve to its initial position when the timing device is de-energized for procuring the movement of the piston and rod to their initial position, means for securing said movable die element and pilot to the piston rod for moving the pilot out of the dimpled aperture, means for releasing the die and pilot near the end of the upward movement of the piston rod for permitting the end of the pilot to again drop into engagement with the surface of the sheet, and means for rendering said releasing means ineffective for interrupting the operation of the device after the pilot has been withdrawn from the sheet.

10

15 2. A device, as in claim 1, in which the rod is tubular and the mating die element is movable therein.

20 3. A device, as in claim 1, in which the rod is tubular and the mating die is movable therein and having resilient means disposed within the tubular rod adapted to impart downward pressure upon the mating die element.
